UNITED STATES PATENT OFFICE.

JOSEPH ECKER, OF NEW YORK, AND ELIAS GOLDBERG, OF CONEY ISLAND, NEW YORK.

DESIGN FOR A GAME-BOARD.

55,418.

Specification for Design.

Patented June 8, 1920.

Application filed December 16, 1919. Serial No. 345,408. Term of patent 7 years.

To all whom it may concern:

Be it known that we, JOSEPH ECKER, a resident of New York city, Bronx county, State of New York, and ELIAS GOLDBERG, a resident of Coney Island, Kings county, State of New York, have invented a new, original, and ornamental Design for a Game-Board, of which the following is a specification, reference being had to the accompanying drawing, forming part hereof, which illustrates a face view of a game-board embodying our new design.

We claim:—

The ornamental design for a game board, as shown.

Signed at New York city, New York, this 10th day of December, 1919.

JOSEPH ECKER.
ELIAS GOLDBERG.
